UNITED STATES PATENT OFFICE

DELBERT F. COBOURN, OF PORTSMOUTH, OHIO, ASSIGNOR TO THE UNION SWITCH & SIGNAL COMPANY, OF SWISSVALE, PENNSYLVANIA, A CORPORATION OF PENNSYLVANIA

APPARATUS FOR CONTROLLING RAILWAY SWITCHES

Application filed June 4, 1930. Serial No. 459,142.

My invention relates to apparatus for controlling railway switches, and particularly to apparatus of the type involving a manual lever located at a distant point for the control of a switch.

One object of my invention is the provision, in combination with apparatus of this type, of auxiliary manually operable means located adjacent the switch for removing the switch from control by the distant lever and holding the switch in the position to which it was last moved.

I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a stretch of railway track which is provided with a switch 3. Switch 3 is operated by a motor M, which as here shown comprises a cylinder 8, containing a reciprocable piston 9 operatively connected with switch 3. Fluid under pressure, usually compressed air, is at times supplied to one end or the other end of cylinder 8 from a suitable source, not shown in the drawing, and the supply of such fluid is controlled by a switch valve designated, in general, by the reference character K. This valve comprises a normal magnet N and a reverse magnet R.

As shown in the drawing, the switch occupies its normal position. If, now, reverse magnet R is energized, fluid pressure will be supplied to motor M to operate switch 3 to its reverse position. If, when the switch occupies its reverse position, magnet N is energized, valve K will supply fluid pressure to motor M to restore switch 3 to its normal position.

Switch 3 operates a contact arm 11 which is arranged to engage a fixed contact member 11^a when the switch occupies its normal position, and a second fixed contact member 11^b when the switch occupies its reverse position.

Switch valve K is controlled in part by a manually operable lever D which may be

one of a number of such levers located in a control cabin at a point remote from switch 3. Lever D operates a normal contact 16 which is closed while lever D is in its normal position, and a reverse contact 15 which is closed while lever D is in its reverse position.

Located adjacent the switch 3 is an auxiliary manually operable circuit controller S which, in the form here shown, is a double throw hand switch having two contact members 4 and 5. When the switch S is in its normal position wherein it is shown in solid lines, member 4 connects wires 19 and 19^a, and member 5 connects wires 29 and 29^a. When this switch is thrown to its reverse position, wherein it is illustrated in dash lines, member 4 will connect wires 61 and 61^a but the circuits through wires 19, 19^a, and 29, 29^a will be broken.

As shown in the drawing, lever D occupies its normal position, controller S is in normal position, and switch 3 occupies its normal position. If the operator in charge of lever D wishes to reverse the switch, he will reverse lever D. The closing of contact 15 of lever D will complete a circuit over which current flows from battery 62, through contact 15, wire 19, contact 4, wire 19^a, reverse magnet R, and wire 22 back to battery 62. Motor M will then be actuated to move switch 3 to its reverse position.

If the operator wishes to restore switch 3 to its normal position, he will return lever D to its normal position, whereupon current will flow from battery 62, through contact 16 of lever D, wire 29, contact 5, wire 29^a, normal magnet N of switch valve K, and wire 22 back to battery 62. Motor M will then restore switch 3 to its normal position.

I will now assume that switch 3 is in the normal position, that one or more cars are located on the side track 6, and that these cars are undergoing repairs, so that it would be dangerous to allow switch 3 to be reversed thereby allowing other cars to enter the side track. Under this condition the person in charge of the repair work will reverse the auxiliary circuit controller S, thereby opening the circuits hereinbefore traced for the normal and reverse magnets N and R, so that

the switch 3 is removed from control by the manual lever D and cannot be reversed by the reversal of this lever. Furthermore, an auxiliary circuit for the normal magnet N will then be closed, which circuit is from battery 62, through wire 61, contact 4 of circuit controller S, wire 61^a, switch operated contact 11-11^a and magnet N to battery 62. This circuit will keep magnet N energized, and will therefore hold the switch 3 in its normal position.

Similarly, if switch 3 is in the reverse position, and there is a car undergoing repairs on the main track 7 beyond the switch, the person in charge of such repairs will reverse the circuit controller S as before, thereby opening the main circuits for magnets N and R and closing the auxiliary circuit for magnet R. This circuit is from battery 62 through wire 61, contact 4, switch circuit controller contact 11-11^b, reverse magnet R, and wire 22 to battery 62. This circuit will keep magnet R energized and will thereby hold the switch 3 in its reverse position so as to prevent additional cars from entering the portion of track containing the car under repair.

Apparatus embodying my invention is particularly well adapted for use in railway classification yards where a plurality of switches similar to switch 3 are used to distribute cars on what is known as a ladder track. In yards of this character it sometimes becomes necessary to carry out repairs to cars after they have been distributed, and heretofore the only protection which has been afforded to men working on such cars is the usual "blue flag". By means of apparatus embodying my invention, the blue flag is supplemented by apparatus which positively prevents a switch from being moved to allow other cars to collide with the car under repairs, and, consequently, the safety of the men, conducting such repairs, greatly enhanced.

In actual practice, the circuit controller S will usually be enclosed in a locked box, the key of which will be in the hands of the person in charge of the car repairs, so that this circuit controller cannot be operated by unauthorized persons.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway switch, a motor for moving said switch to normal and reverse positions, a manually operable lever located at a remote point for the control of said motor, a circuit controller operated by

said switch and normally ineffective to control said motor, and auxiliary manually operable means located adjacent said switch for removing the motor from control by said lever and placing it under control of said circuit controller.

2. In combination, a switch mechanism comprising a normal and a reverse magnet, a railway switch operable to normal or reverse position according as said normal or reverse magnet is energized, a normal switch contact closed when said switch is in said normal position, a reverse switch contact closed when said switch is in reverse position, a manual lever for the control of said switch comprising a normal and a reverse contact, a main circuit for said normal magnet including said normal lever contact, an auxiliary circuit for said normal magnet including said normal switch contact, a main circuit for said reverse magnet including said reverse lever contact, an auxiliary circuit for said reverse magnet including said reverse switch contact, and manually operable means for opening said main circuits and closing said auxiliary circuits to prevent control of the switch by said lever and to hold the switch in the position to which it was last moved.

In testimony whereof I affix my signature.

DELBERT F. COBOURN.
